(57) **CLAIM**

The ornamental design for a cap for bottle, as shown and described.

DESCRIPTION

This application is related to co-pending application Ser. No. 14/746,965, which are incorporated herein by reference.

FIG. 1 is a top, front and left side perspective view of a cap for bottle showing our new design;

FIG. 2 is a top, rear and left side perspective view thereof;

FIG. 3 is a top plan view thereof;

FIG. 4 is a bottom plan view thereof;

FIG. 5 is a left side elevational view thereof; the right side elevational view being a mirror image;

FIG. 6 is a front elevational view thereof; and,

FIG. 7 is a rear elevational view thereof.

The broken lines in the drawing depict portions of the cap for bottle that form no part of the claimed design.
